UNITED STATES PATENT OFFICE.

WILLIAM C. MORRILL, OF NEW YORK, N. Y.

LIQUID-DISCHARGING DEVICE.

SPECIFICATION forming part of Letters Patent No. 743,093, dated November 3, 1903.

Application filed May 28, 1903. Serial No. 159,134. (No model.)

To all whom it may concern:

Be it known that I, WILLIAM C. MORRILL, a citizen of the United States, residing in the city of New York, borough of Manhattan, and 5 State of New York, have invented certain new and useful Improvements in Liquid-Discharging Devices, of which the following is a specification thereof.

The invention relates to a novel device for 10 controlling and discharging a predetermined quantity of liquid from a vessel or receptacle containing the same.

The invention consists of a multichambered reciprocating body working in conjunction 15 with fixed devices for opening and closing said chambers and discharging the contents therefrom as supplied by a vessel or receptacle with which the invention may be connected, all of which will be fully shown, and pointed 20 out in the claims hereinafter described.

In the drawings, Figure 1 represents an elevational and vertical section of the device properly secured to the mouth of a receptacle, a portion of the latter being here shown 25 in section, and the dotted lines represent the line of movement assumed by the reciprocating multichambered body. Fig. 2 represents a modification of the multichambered reciprocating body shown in section, which also 30 shows a modified form of the plunger. Fig. 3 is a modified form of the multichambered body shown in section. Fig. 4 is a sectional and elevational view of the device slightly modified with respect to the fixed plunger or 35 piston. Fig. 5 is also a similar view to that of Fig. 4 and is here shown to have a part of its fixed plunger or piston movable with the reciprocating multichambered body. Fig. 6 represents a transverse section taken on line 40 XX of Fig. 4.

Similar characters refer to similar parts throughout the drawings, in which—

a represents the wall of a receptacle, which may be constructed of vitreous vegetable fiber 45 or metallic substances. This feature, however, will be a matter of choice to suit the condition or circumstances of the locality where the device may be permanently fixed. The yoke-stopper holder b is properly secured 50 within the mouth of the receptacle a by any suitable means known in the state of the art to which it appertains. The base c of the se-

curing-stopper b is provided with the centrally-located aperture d, the latter of which is adapted to receive the reciprocating body 55 e, the interior of which is composed of the piston-chamber f, supply-chamber g, and discharge-chamber h. The chambers f and g are divided, as shown, by the fixed packing i, the central opening of which moves reciprocally upon the fixed plunger-head or piston k, provided with a depending cleaner l, adapted to pass through the discharge-orifice m when the latter shall have been brought up to it. The two plunger or piston heads k 60 and k' are connected one with the other by means of the rod n. The plunger or piston head k may be made as shown, or it may be made fixed to the yoke o by means of the securing-nut p. The reciprocating multi-chambered body e is provided with a retracting device, which in this instance is represented by a spring r. The upper end of 65 said reciprocating body e is provided with a suitable detent adapted to limit its downward throw. The lower end of the said body e may be flayed outward in a manner that will not mark the hand when operating the same. The wall of the flayed or flared portion s is provided with the air-vent t, the 70 object of this vent being that when the liquid is forced into the hand on the upward stroke the displaced air is forced through the vent and on the downward stroke the air required to replace the ejected liquid is taken 75 in through the vent.

The operation of the device will be fully described hereinafter.

Mode of operation: It will be obvious that the device herein described is adapted to be 90 used in connection with any form of liquid known to the trade. I will now endeavor to describe the operation of the device when used in connection with liquid soap. The liquid soap is poured into the receptacle through 95 an opening at the top thereof and then perfectly closed. It will here be obvious that the upper or piston chamber f will at all times overflow with the liquid soap. When the operator desires to obtain the soap for 100 cleansing the hands, he has simply to place the palm of one hand under and against the flared portion s of the reciprocating body e and press upwardly. This operation carries

the packing *i* up and above the cone portion of the fixed plunger *k* and allows the liquid soap to be forced down into the supply-chamber *g* by means of the adjustable fixed plunger *k'*. The soap thus forced into the supply-chamber will displace a corresponding amount of soap already there, causing it to discharge through the discharging-orifice *m* into the hand of the operator. When the pressure of the hand shall have been removed from the reciprocating body *e*, it will assume its normal condition automatically by the action of the retracting-spring *r*. It will be obvious that the quantity delivered to the consumer or operator will be regulated by the position of the adjustably-fixed plunger *k'*, which may be lowered or raised, as desired. As a matter of precaution the cleaner *l* is adapted to pass through the discharge-orifice 20 when the upward stroke shall have been completed, thus keeping the opening clear at all times for use.

The periodical use of the device will of course cause the external surface of the reciprocal body *e* to wear away by frictional contact with the wall of the opening of the yoke-stopper *b*, and to provide for this condition the yoke-stopper is provided with the packing *u*, thus preventing the contents of the receptacle leaking therefrom.

In the modification shown in Fig. 2 the packing within the reciprocal body is dispensed with and a flap-valve 2 adopted in lieu thereof.

35 The modification shown in Fig. 3 shows but two chambers, which may work in conjunction with any desired mechanism for opening up communication of one chamber with the other.

40 In Fig. 4 the lower end of the adjustable fixed plunger or piston 3 is at all times seated within the piston-chamber *f'* and is fluted vertically, as shown. The object of the fluting or perforations of the plunger or piston is to allow the liquid soap to flow into the said piston or plunger chamber *f'*.

45 In the modification shown in Fig. 5 the adjustable fixed plunger or piston 5 is made the same externally as that shown in Fig. 4, with the exception of the central piston or plunger rod 4, which in this case forms a puppet-valve at its lower end, while its upper end moves upwardly within said plunger 5. The communication between the upper and lower 50 chambers of the reciprocating body 6 is kept normally closed by the spring in the lower chamber and is opened when the plunger-rod

4 shall have reached the end of its stroke within the plunger or piston 5, as shown. It will be obvious that many forms may be 60 made without departing from the spirit of the invention.

Having thus described the invention, what I claim as new, and desire to secure by Letters Patent, is—

65 1. In a liquid-discharging device the combination consisting of a multichambered reciprocating body adapted to work in conjunction with fixed devices for opening and closing communication of said chambers and removing the contents from the interior thereof, the whole connected with a liquid-containing receptacle substantially as set forth.

70 2. In a liquid-discharging device the combination consisting of a reciprocating chambered body, a normally stationary piston or plunger capable of adjustment, a depending rod, a cone-head cylindrical plunger or piston secured to the aforesaid depending rod, the cleaner connected with the lower end of 80 said cone-head plunger or piston, the whole to be worked upon by the reciprocating chambered body, substantially as set forth.

75 3. In a liquid-discharging device the combination of a multichambered reciprocating body, a yoke-stopper holder, the normally stationary adjustable plunger or piston connected therewith, the whole adapted to work in conjunction with the multichambered reciprocating body, substantially as set forth.

80 4. In combination with a liquid-discharging device of the fixed plunger, the vertical reciprocating body the piston-chamber, the fixed packing, the supply-chamber, provided with a discharge-orifice arranged at the bottom thereof, substantially as set forth.

85 5. In combination with a liquid-discharging device of the fixed piston and the multi-chambered reciprocating body having the flared lower end and the wall thereof provided with the air-vent, substantially as set forth.

90 6. In a liquid-discharging device the combination of a multichambered reciprocating body and the adjustably-fixed pistons or 105 plungers with the retracting device, substantially as set forth.

95 In testimony whereof I have hereunto set my hand this 27th day of May, 1903.

WILLIAM C. MORRILL.
